UNITED STATES PATENT OFFICE.

GEORGE F. BEEBE, OF QUINCY, ILLINOIS.

DESIGN FOR PICTURE OR OTHER FRAMES.

Specification forming part of Design No. 7,488, dated June 9, 1874; application filed June 1, 1874.

[Term of Patent 7 years]

To all whom it may concern:

Be it known that I, GEORGE F. BEEBE, of Quincy, in the county of Adams and State of Illinois, have invented a Design for an Ornamental Frame for Pictures, Advertising Tablets, &c., of which the following is a specification:

My design is fully represented in the accompanying photolithographic illustration, to which reference is made.

A represents the body of the frame, which is divided vertically and horizontally into a number of rectangular panels, *a a'*, forming separate and distinct compartments, intended to contain pictures, tablets, or other devices for display. The pilasters and horizontal bars separating these panels are faced with ornamental bead or scroll work *b*. The lower portion of the pilasters or upright frame and partition bars are provided with a number of ornamental pockets, B, corresponding in number to the number of panels in the frame. The two central panels *a'* are made of a length from top to bottom equal to three of the panels *a*. A base plate or bar, D, extends across the bottom of the frame, ornamented by suitable ogee brackets, resting upon uprights or standards E, with ornamental brackets e. On the body A of the frame is placed an ornamental cornice and pediment, F G, the pediment divided, like said body, into panels *G' g g' g''*, the center and end panels rising above those intermediate between them, the large center one, *G'*, containing between the cornice F and the gable-roof form of cap or cornice *F'* a time or clock dial, H, and is surmounted with a finial, *h*. The end panels *g* are covered by an orn-

mental cornice, *F''*, arched in form, and provided each with a finial, *h'*. The intermediate panels *g' g''* are of less height than the panels *G' g*, as stated, and a molding extending from the cornice *F'* to a point about midway of the height of the panel *G*; thence extends outward horizontally to about midway of the width of panel *g'*, whence it descends by vertical and curved lines cutting the outer corner of panels *g'* to a point about midway of the height of the end panels *g*, where it connects with the molded upright at the inner side of said panels, as shown. The uprights between the panels in the pediment are faced with ornamental rolls or beads *i*, and the angles in the molding at the side of panel *G* and over the panels *g' g''* are filled in by ornamental scrolls I.

Rosettes *k k'* may be applied around the dial and at the ends of the beads *b*, as shown, but are not deemed essential.

I have shown a series of time-dials in some of the compartments; but these form no part of my invention or design, and such I do not claim.

The frame having the ornamental design and configuration shown and described may be of grained woods for giving additional beauty and finish.

What I claim as my invention is—

The design for an ornamental frame having the configuration and ornamentation herein described and shown.

GEORGE F. BEEBE.
